UNITED STATES PATENT OFFICE.

HALBERT K. HITCHCOCK, OF PITTSBURGH, PENNSYLVANIA, ASSIGNOR OF ONE-HALF
TO HITCHCOCK EXPERIMENT COMPANY, A CORPORATION OF NEW JERSEY.

LEER.

Application filed August 9, 1921. Serial No. 490,836.

To all whom it may concern:

Be it known that I, HALBERT K. HITCHCOCK, a citizen of the United States, and a resident of Pittsburgh, in the county of 5 Allegheny and State of Pennsylvania, have made a new and useful invention in Improvements in Leers, of which the following is a specification.

The invention relates to leers and is particularly designed for service in the drawing of glass continuously in sheet form. It has for its principal objects the provision of a leer construction having improved means for regulating the temperature of the 10 leer in varying degree throughout its length, the provision of an improved construction for dividing the leer into separate compartments, and the provision of an improved form of roller construction and drive therefor. One embodiment of the invention is 15 illustrated in the accompanying drawings, wherein:

Figure 1 is a front elevation of the leer, with a part of the supporting frame work 20 in section; Fig. 2 is a similar side elevation of the leer; Fig. 3 is a partial section and partial side elevation of one portion of the leer, the upper half of the figure being a section on the line III—III of Fig. 4 and the lower half being a side elevation; Fig. 4 is a vertical section on the line IV—IV of Fig. 3; Fig. 5 is a partial horizontal section on the line V—V of Fig. 4; Fig. 6 is 25 an enlarged detailed section taken at the edge of one of the drawing rolls; and Fig. 7 is an enlarged plan view of one of the strands of asbestos cord used upon the drawing pulleys.

Referring to the general arrangement 30 shown in Figs. 1 and 2, the framework for supporting the vertical leer casing comprises the four upright corner channels 1, the main horizontal channels 2 arranged in four sets at different levels and the diagonal braces 3. At the center of this framework is the leer 35 casing in the form of a vertical box, rectangular in cross section, located above and in alignment with the slot member 4, located in the molten bath, such slot member being shown in dotted lines, although it will be 40 understood that the character of the molten bath from which the glass is drawn is immaterial in so far as the leer construction of the present invention is concerned. The casing 45 is divided vertically into a plurality of

separate compartments 5, 6, 7, 8, 9, 10, 11, 12 and 13 by the inclined pairs of diaphragm walls 14. These diaphragm walls are constructed as indicated in Fig. 3, comprising a sheet metal member 15, and plate 16, and 50 an intermediate asbestos packing 17, the upper ends of the walls terminating short of the center line of the leer and being provided at this point with a construction for permitting the passage of the sheet and yet at the same time making a comparatively tight joint with the glass to prevent the passage of heat from one chamber to the next. This object is accomplished by the provision of the asbestos sheets 18 clamped at their lower 55 edges between the pairs of asbestos plates 19, which latter plates fit loosely over the upper edge of the plate 16. The lost motion connection between the plates 18 and the diaphragm walls 14 is necessary in order to permit the passage of a sheet of varying thickness and also to permit the passage of the bait employed for initiating the operation. In order to spread the plates 18 apart before the bait arrives, separator devices 20, 60 carried at the side walls of the leer casing upon vertically movable rods 21, may be employed. These rods are moved vertically to cause the members 20 to engage the plates 18 and separate them by means of the lever 22 shown in Fig. 2 and having its end 23 connected to the upper end of one of the rods 21.

The leer casing is divided into sections 65 which are independently supported from the surrounding framework in order to take care of the expansion and contraction of the casing, which would tend to buckle it and interfere with the operation of the roller mechanism carried in the casing. The sections are therefore hung from the sets of 70 main transverse channels 2—2—2 with telescopic joints at the abutting ends of the sections, one of such joints being shown at 75 24 in Fig. 3. As here shown, the shell of 80 the one casing member telescopes inside the shell of the member just below, so that the two ends are free to move relatively in a vertical direction. With sections as short as the 85 ones used here, this relative movement is, of course, slight, and a tight joint is insured by placing an asbestos packing 25 between the edges of the opposing angles 26 and 27, such angles being riveted to the opposing 90 ends of the two sections.

110

As shown in Fig. 3, the front and back walls of each chamber, such as the chamber 7, are provided with hollow walls which give the spaces 28 and 29, and the outer wall 5 of these spaces is preferably provided, as indicated at Fig. 5, with an insulating coating 30 of asbestos. The spaces 28 and 29 may be heated with gas burners extending through the openings 31, the upper openings 32 serving as exits for the gases of combustion. The temperature of each of the chambers or compartments 5 to 13 may in this way be regulated so as to give the gradually decreasing temperature from the 10 lower to the upper end of the leer in order to provide for annealing the glass and for reducing it to a temperature at which it is safe to bring it into the outer air and cut it off. Additional temperature controlling 15 means are also provided upon the side walls of the leer casing. As indicated in Fig. 3, in conjunction with Figs. 4 and 5, hollow walls are also provided upon these sides of the leer casing, giving the chambers 33 and 20 34. A gas and air mixer discharges into the opening 35 at the lower corner of the chamber 33, and the gases of combustion are carried transversely through this chamber 33 to the outlet 36, at which point a pipe 25 37 carries the hot gases to the inlet 38 of the chamber 34. From this point the gases pass to the outlet 39 of the chamber 34 and thence upward through the pipe 40 to an inlet opening in the next heating chamber 30 35 corresponding in position to the inlet opening 35. The gases of combustion are in this way carried up through the heating chamber on the sides of the three compartments 5, 6 and 7, after which they are discharged. 40 A similar arrangement provides for the heating of the hollow front and rear walls of the compartments 8, 9 and 10 and also of the walls of the compartments 11, 12 and 13. In this way the heating of the chamber and 45 the regulation of the temperature inside the casing supplements the regulation of the heating secured from the sets of chambers 28 and 29 at the front and rear of the casing heretofore referred to, and the temperature of the glass is controlled from the time it enters the leer until it passes out at the 50 upper end, suitable pyrometers and automatic regulating devices being used if desired, to give the desired temperature in each of the compartments 5 to 13. In order to permit of the removal of broken glass from the compartments and to give access to the interior of the construction for other purposes, the portions of the walls marked 55 41 in Fig. 3 are made of single thickness instead of being made hollow, and are bolted removably in position.

In each of the compartments of the leer are a pair of roll members for advancing 60 the sheet of glass. Each of these roll mem-

bers comprises a shaft upon which are mounted a plurality of rolls, each of which is supported flexibly so that the roll members may adjust themselves to inequalities of the sheet and avoid imposing a crushing strain in case the sheet should be warped or of uneven thickness. This construction is shown in detail in Figs. 4 and 5, which will be readily understood by reference thereto in connection with Fig. 3, and it will be understood that these roll constructions are the same in all of the compartments so that a description of one will be sufficient for all. This roll construction constitutes an improvement on the construction shown and claimed in my Patent No. 832,860 of November 21st, 1905. As indicated in Fig. 5 in connection with Fig. 3, the opposing sets of rolls 42 and 43 are mounted upon the shafts 44 and 45, the shafts themselves being journaled at their ends in the upper ends of the levers 46 and 47. Lying immediately below the shafts 44 and 45 in vertical alignment therewith are what may be called the supporting shafts 48 and 49 (Fig. 4), and the levers 46 and 47, which carry the roll shafts 44 and 45, are pivoted upon these supporting shafts. The supporting shafts are mounted in bearings 50, 51 and 52 located outside of the leer compartment (Fig. 4) and supported upon transverse frame members 53, 54 and 55, which constitute a part of the framework surrounding the leer casing. The roll shafts are pressed yielding toward each other by the springs 56 and 57 (Fig. 3) mounted upon the shaft 58 and being regulated as to compression by means of the nuts 59. The movements of the rolls away from the center line 60 of the leer are made equal by the use of the connecting rods 61 (Fig. 3), such connecting rods being pivoted at their ends to the levers 46 and 47, so that the movement of one roll outward from the center line 60 causes the other roll to move out an equal distance.

Flexible mounting of the rolls 42 and 43 upon the shafts 44 and 45 is accomplished as indicated in Fig. 4, a collar 62 keyed to the shaft 44 being provided intermediate each pair of rolls. This collar carries three transverse rods 65 mounted for universal movement in the collar as indicated at 66. These shafts carry at their ends the ball members 67 mounted for universal movement in the hubs of the rolls as indicated in Fig. 4. This arrangement provides for the adjustment of the rolls to any inequalities of the sheet to prevent breakage due to such inequalities. In order to give these rolls a yielding refractory surface, which will not mar the glass and which will be serviceable throughout a long continued period of use, a wrapping of asbestos cord is provided as shown in detail in Figs. 6 and 7. This cord is wrapped cir-

centrally of the roll and comprises a central wire of copper or composition 68 surrounded by a woven fabric of asbestos, each strand of which has a core 69 of wire. This fabric is woven or braided around the wire with what is known as the may-pole weave or braid, the threads of the fabric intermeshing as indicated in Fig. 6. This construction gives a pulley coating which is exceedingly resistant to wear as the weave of small wires through the fabric tends to hold the fabric together and give it the necessary tensile strength. The wire in the center gives the cord the additional reinforcement necessary to prevent it from being broken under strain, and clamp it to the drum.

The supporting shafts 48 and 49 serve to maintain the rolls on opposite sides of the sheet in the same horizontal alignment, so that pressure is applied upon the sheet on lines which are in the same horizontal plane, thus avoiding any breakage such as might occur where flexibly mounted rolls are employed, in which the horizontal center lines were capable of being thrown out of alignment during the drawing operation. These supporting shafts are provided with collars 70, which engage the metal of the rolls outside the asbestos winding. The supporting shafts are preferably driven so that the collars 70 have the same peripheral speed as that of the rolls 42, so that there is no retarding effect incident to the employment of the supporting rolls. The driving connection between the roll shafts and supporting rolls is secured by means of the gear 71 on the roll shafts which engage pinion 72 on the supporting shafts. The outer ends of the supporting shafts 48 and 49 are driven by means of the sprocket wheels 73 and 74, whose opposing toothed flanges overlap and engage the driving sprocket chain 75, as indicated in Figs. 3 and 5. The driving sprocket chain 75 is arranged as shown in Fig. 2 and extends in a vertical plane from the bottom of the leer casing to the top, passing between all the sets of sprocket wheels 73 and 74. After passing the set of sprocket wheels for the compartment 18, the chain passes over the idler sprockets 75^a and 76, the latter being yieldingly supported in the bearing member 77, whose shaft is threaded for adjustment through the nut 78 and is yieldingly supported by the coil spring 79. The chain extends downward from the sprocket 76 to the lower end of the casing, where it passes around the pair of sprockets 80 and 81, the latter sprocket being mounted upon a counter shaft 82, which is driven by a chain 83 passing around the sprocket on the shaft 84 of the motor 85. The roll shafts are in this manner all driven at a constant speed and effect a drawing of the glass by means of the flexibly mounted rolls which are yieldingly pressed against the glass with a force which

may be adjusted to suit conditions and which will effect the drawing of the glass even though the sheet is somewhat out of true, due to warping and varying thickness.

As the glass cools more rapidly at its edges than in the intermediate portion in passing from the bath to the leer, it is desirable to apply more heat to such edges than at the central portion of the sheet after it enters the leer. The walls of the leer opposite the edges of the sheet are therefore more highly heated than the walls opposite the sides in the lower portion of the leer. As the sheet progresses upwardly it gradually arrives at a uniform temperature from edge to edge, and in the upper end of the leer before the sheet emerges therefrom the temperatures of all four walls of the leer are brought to the same temperature.

What I claim is:

1. In combination in a leer for annealing a glass sheet drawn continuously from a molten bath, a vertical leer casing having hollow walls, drawing means arranged along the length of the casing for engaging the glass and advancing it therethrough, transverse partitions arranged at intervals along the length of the casing dividing it into a plurality of compartments, and heating means for the hollow walls of each compartment so that the temperature of the various compartments may be independently regulated.

2. In combination in a leer for annealing a glass sheet drawn continuously from a molten bath, a vertical leer casing having hollow walls, drawing means arranged along the length of the casing for engaging the glass and advancing it therethrough, transverse partitions arranged at intervals along the length of the casing dividing it into a plurality of compartments, the said partitions having slots to permit the passage of the glass sheet, and sheets of woven refractory material for closing the clearance spaces between the edges of the partitions at the slots and the glass.

3. In combination in a leer for annealing a glass sheet drawn continuously from a molten bath, a vertical leer casing having hollow walls, drawing means arranged along the length of the casing for engaging the glass and advancing it therethrough, transverse partitions arranged at intervals along the length of the casing dividing it into a plurality of compartments, the said partitions having slots to permit the passage of the glass sheet, and yielding refractory means carried by the partitions at the slots and engaging the glass sheet for closing the clearance spaces between the edges of the slots and the sides of the glass sheet.

4. In combination in a leer for annealing a glass sheet drawn continuously from a molten bath, a vertical leer casing having hollow walls, drawing means arranged

- along the length of the casing for engaging the glass and advancing it therethrough, transverse partitions arranged at intervals along the length of the casing dividing it into a plurality of compartments, the said partitions having slots to permit the passage of the glass sheet, and inclined yielding sheets of asbestos carried by the partitions and adapted to engage the glass sheet.
10. 5. In combination in a leer for annealing a glass sheet drawn continuously from a molten bath, a vertical leer casing having hollow walls, drawing means arranged along the length of the casing for engaging the glass and advancing it therethrough, transverse partitions arranged at intervals along the length of the casing dividing it into a plurality of compartments, the said partitions having slots to permit the passage 20 of the glass sheet, and yielding means carried by the partitions at the slots and engaging the glass sheet for closing the clearance spaces between the edges of the slots and the sides of the glass sheet, said yielding means being mounted with lost motion connections to permit of the passage of a bait through the slots.
6. In combination in a leer for annealing continuously formed sheet glass, a vertical 30 framework, an annealing casing extending vertically upward inside said framework and comprising a series of aligned sections in telescopic relation, and means for supporting the sections independently from the framework.
7. In combination in a leer for annealing continuously formed sheet glass, a vertical framework, an annealing casing extending vertically upward inside said framework 40 and comprising a series of aligned sections in telescopic relation, packing means at the joints between the sections, and means for supporting the sections independently from the framework.
45. 8. In combination in a leer for annealing continuously formed sheet glass, a vertical framework, an annealing casing extending vertically upward inside said framework and comprising a series of aligned sections 50 having their adjacent ends relatively movable, and means for supporting the sections independently from the framework.
55. 9. In combination in a leer for annealing continuously formed sheet glass, a vertical framework, an annealing casing extending vertically upward inside said framework and comprising a series of aligned sections having their adjacent ends relatively movable, glass advancing means for each section, and means for supporting each section 60 and its advancing means from the framework independent of each other section and its advancing means.
65. 10. In combination in a leer for annealing continuously formed sheet glass, a leer cas-

- ing, a plurality of sets of opposing rolls spaced along the leer for advancing the glass therethrough, a pair of opposing toothed driving sprockets for each pair of rolls, having their toothed peripheries overlapping, and a chain for driving said sprockets, said chain extending between each pair of sprockets and engaging both sets of overlapping teeth on the opposing sprockets.
11. In combination in a leer for annealing continuously formed sheet glass, a leer casing, a pair of opposing roll shafts extending across the casing, a plurality of rolls flexibly mounted on each shaft to permit the rolls to conform themselves to the contour 70 of the glass sheet which is being drawn, and a supporting shaft lying beneath each of the roll shafts and in engagement with the peripheries of the rolls upon such shafts.
12. In combination in a leer for annealing continuously formed sheet glass, a leer casing, a pair of opposing roll shafts extending across the casing, a plurality of rolls flexibly mounted on each shaft to permit the rolls to conform themselves to the contour 75 of the glass sheet which is being drawn, a supporting shaft lying beneath each of the roll shafts and in engagement with the peripheries of the rolls upon such roll shafts, and means for driving the supporting shafts.
13. In combination in a leer for annealing continuously formed sheet glass, a leer casing, a pair of opposing roll shafts extending across the casing, a plurality of rolls flexibly mounted on each shaft to permit the rolls to 80 conform themselves to the contour of the glass sheet which is being drawn, a supporting shaft lying beneath each of the roll shafts and in engagement with the peripheries of the rolls upon such roll shafts, and means for driving the supporting shafts.
14. In combination in a leer for annealing continuously formed sheet glass, a leer casing, a pair of opposing driven roll shafts extending across the casing and mounted for movement toward and from each other, a plurality of rolls flexibly mounted on each shaft to permit the rolls to follow the contour of the glass passing the rolls, a supporting shaft lying beneath each of the roll shafts and in engagement with the peripheries of the rolls upon such roll shafts, and means for driving the supporting shafts.
15. In combination in a leer for annealing continuously formed sheet glass, a leer casing, a pair of opposing driven roll shafts extending across the casing, a plurality of rolls flexibly mounted on each shaft, a supporting shaft lying beneath each of the roll shafts and in engagement with the peripheries of the rolls upon such roll shafts, bearings for the supporting shafts, lever arms 110 in which the roll shafts are pivoted and 115
- 120
- 125
- 130

- which are themselves pivoted on the supporting shafts, gear connections between the roll shafts and supporting shafts, and a link connection between the lever arms.
5. 16. In combination in a leer for annealing continuously formed sheet glass, a leer casing, a pair of opposing driven roll shafts extending across the casing, a plurality of rolls flexibly mounted on each shaft, a supporting shaft lying beneath each of the roll shafts and in engagement with the peripheries of the rolls upon such roll shafts, bearings for the supporting shafts, lever arms in which the roll shafts are pivoted and which are 10 themselves pivoted on the supporting shafts, gear connections between the roll shafts and supporting shafts, a link connection between the lever arms, and means for rotating the supporting shafts.
15. 17. In combination in a roll for use with sheet glass, a metal pulley and an asbestos cord facing wound on the periphery of the pulley, the said cord comprising a central wire with an asbestos fabric woven around it, and the strands of asbestos fabric having 20 wire centers.
18. In combination in a roll for use with sheet glass, a metal pulley and an asbestos cord facing wound on the periphery of the 25 pulley, the said cord comprising a central wire with an asbestos fabric woven around it in an intermeshing braided form and the strands of asbestos fabric having reinforcing centers of fine wire.
30. 19. In combination in a leer for annealing a glass sheet drawn from a molten bath, a vertical casing, drawing means for advancing the glass through the casing, partitions dividing the casing into a plurality of compartments and means for heating the walls of the compartments at different levels independently to control the cooling of the sheet 35 as it is drawn.
40. 20. In combination in a leer for annealing a glass sheet drawn from a molten bath, a vertical casing divided into a plurality of compartments one above the other drawing means for advancing the sheet through the casing, means for heating the walls of the 45 compartments opposite the sides of the sheet 50 and other means for heating the walls of the compartments opposite the edges of the sheet.
21. In combination in a leer for annealing a glass sheet drawn from a molten bath, a vertical casing divided into a plurality of compartments one above the other drawing means for advancing the sheet through the casing, means for heating the walls of the compartments opposite the sides of the sheet 55 and other means for heating the walls of the compartments opposite the edges of the sheet, the said heating means being arranged to give a gradually decreasing temperature 60 in the compartments from the bottom up. 65
22. In combination in an apparatus for annealing a glass sheet drawn from a molten bath, a vertical annealing leer above the bath having a series of temperatures in the succeeding portions thereof, gradually decreasing from the bottom upward, and a plurality of vertically spaced heating means for controlling and regulating the cooling of the edges of the sheet by varying the temperature of the leer opposite the edges of 70 the sheet. 75
23. In combination in a roll for use with sheet glass, a metal pulley, and an asbestos cord facing wound on the periphery, the said cord comprising a central wire with 80 an asbestos fabric woven around it. 85
24. A process for annealing a sheet of glass drawn upward from a glass bath through an annealing leer which consists in first passing the sheet through a section in the leer in which a higher degree of heat is applied to the edges of the sheet than to the intermediate portion, to bring the sheet to a uniform temperature, and then passing it through a section in which the degree of heat applied to the edges is the same as that applied to the sides of the sheet, the degree of heat applied to the sheet being gradually decreased as the sheet progresses upwardly 90 through the leer. 95
- In testimony whereof, I have hereunto subscribed my name this 30th day of July, 1921.

HALBERT K. HITCHCOCK.
